HUMIDIFIER BOTTOM

Olin S. Elliott, Spartanburg, S. C.

Application December 29, 1934, Serial No. 759,786

9 Claims. (Cl. 261—116)

This invention relates to the class of air conditioning and pertains particularly to humidifiers.

The primary object of the present invention is to provide an improved form of bottom construction for a humidifier by which dripping of moisture from the same is prevented.

Another object of the invention is to provide an improved humidifier bottom which is so constructed as to be easily cleaned without having to disassemble the structure.

The invention broadly contemplates the provision in a humidifier of a bottom having a centrally raised area leading downwardly and outwardly to a deck portion across which the vapor laden air is discharged. The outer edge of this deck has attached thereto a trough unit designed to catch any drops of moisture which may fall from the edge of the deck and having an outer wall which has its top edge in a plane below the deck so that the air will not come into contact therewith.

The invention will be best understood from a consideration of the following detailed description taken in connection with the accompanying drawing forming part of this specification, with the understanding, however, that the invention is not confined to any strict conformity with the showing of the drawing but may be changed or modified so long as such changes or modifications mark no material departure from the salient features of the invention as expressed in the appended claims.

In the drawing:—

35 Figure 1 is a view in vertical section of a humidifier showing the bottom construction embodying the present invention.

Figure 2 is a sectional view taken upon the line 2—2 of Figure 1.

40 Figure 3 is a vertical section through a supporting lug for an element of the humidifier.

Figure 4 is a plan view of a portion of the inner trough showing a detailed construction.

45 Figure 5 is a sectional view through the inner trough and the lower edge of the bell showing the means connecting the two together.

50 Referring to the drawing wherein like numerals of reference designate corresponding parts throughout the views, the numeral 1 indicates hanger straps by means of which the humidifier structure is suspended from a ceiling or other elevated support. These straps at their lower ends are attached to the ends of arms 2 which are joined to a central ring 3 upon which may be

supported the mounting arms 4 for an electric motor 5.

Suspended from the ring 3 is a downwardly directed cylinder 6 which is open at its upper and lower ends and which has in the upper end the fan 7 which is attached to the shaft of the motor 5 in the manner illustrated. Disposed directly beneath the center of the fan 7 is a water spray nozzle 8 to which a valve pipe line 9 leads.

The ends of the arms 2 also support the hanger straps 10 which at their lower ends have secured thereto the bottom unit for the humidifier which is indicated as a whole by the numeral 11 and which constitutes a portion of the present invention.

15 Telescopically receiving the cylinder 6 in its upper end is a lower shiftable cylinder 12, the bottom portion of which is flared outwardly to form the bell 13. This bell portion of the lower cylinder extends into an inner trough 14 which 20 has an inner inwardly inclined wall 15 which is disposed in spaced relation beneath the lower edge of the bell 13. The bottom edge of the bell is in spaced relation with the bottom of the trough 14 so that there is thus formed a passage- 25 way between the bell and the inner wall of the trough for the flow of moisture condensed on the bell into this trough.

The outer wall of the trough 14 has the outwardly directed flange 16 which normally rests 30 upon the supporting lugs 17 which are secured to the suspension straps 10 by means of the screw bolt 18. These screw bolts pass through elongated slots 19 in the straps 10 so that the adjustment of the lugs on the straps may be accomplished for regulating the height of the trough 14 and the other parts associated therewith relative to the bottom unit 11.

35 While any suitable means may be employed for connecting the bell 13 with the inner trough the means here illustrated consists of a series of spacing sleeves 13' disposed between the bell and the inner wall 15 of the trough, and bolts 14' passing through the bell and trough wall and the interposed sleeves.

Attached to the hanger straps 10 above the lugs 17, are additional lugs 20 which are employed for supporting the bell 13 and the cylinder of which it forms a part together with the trough 14, when the cleaning of the humidifier is necessary, and to permit this, the flange 16 is provided with a pair of recesses 16' through which the lugs 20 may pass after which by turning the bell and trough the flange may be brought to rest on the lugs.

The bottom proper which is indicated generally by the numeral 11 consists of a disk of metal having the central upwardly directed cone-like portion 21 which is concentric with and extends upwardly into the bell 13, and the surrounding deck portion 22, the top surface of which is at an inclination from the horizontal so that the outer edge 23 is at an elevation above the line 24 where the deck joins the cone portion 21, which line might be designated the inner edge of the deck. The lower ends of the hanger straps 10 are secured to the deck 22, as indicated at 25, so that the entire bottom unit is supported by these straps.

15 At intervals about the bottom of the inner trough 14, openings are formed from which lead downwardly the gutters 26, the lower ends of which rest upon the deck 22 in the manner illustrated. These gutters have their open sides 20 directed toward the outer edge of the deck so that the air which will be blown downwardly through the cylinders 6 and 12 by the fan 7 will strike the backs of the gutters as it passes out between the deck and the bottom of the trough 25 14.

The numeral 21 indicates an outer trough which is disposed concentrically with the deck 22 and beneath the same. This outer trough has a vertical inner wall 28 which is joined at 30 its top edge with the under side of the deck along a line spaced inwardly from the deck edge so that the edge 23 of the deck overhangs the back wall of the trough, as illustrated. The forward wall of the trough 27 is preferably 35 slightly inclined outwardly in the manner illustrated and has its top edge in a plane lying well below the edge 23 of the deck. This outer trough 27 is also provided with drain means 29 by which water collected therein may be carried 40 off.

In humidifiers of the type at present in use, the construction of the bottoms is such in each case that the moisture laden air passes over an unguarded edge and any of the moisture carried 45 by the air which may condense upon the bottom is expected to flow back to the center of the bottom which is usually in the form of a sump. However, in actual practice, all of the moisture does not flow back to the sump but because of 50 the accumulation of lint and dust around the outer edge of the bottom, the moisture is retained and forms drops around this edge which fall off onto the floor of the room in which the humidifier is disposed.

55 In the present invention the construction is such that as the moisture laden air is driven down through the cylinders 6 and 12, it will pass out through the passage provided between the trough 14 and the deck 22. Any vaporized moisture which may condense on the wall of the cylinder 12 and the bell 13 will flow down between the bell and the inner wall 15 of the trough 14 into the latter trough from which it will pass downwardly onto the deck 22 by way 60 of the gutters 26. Since the gutters are disposed with their backs opposed to the flow of air, this transferal of the moisture will be effected without any of the same being blown in the form of large drops into the air as would be 65 the case if the condensed drops were permitted to fall freely through the air from the trough to the deck. The air after passing between the trough 14 and the rear part of the deck, is then directed outwardly from the surface of the deck 70 at a slightly upward inclination so that it passes

into the surrounding air without coming into contact with any other parts of the humidifier. However, as the formation of drops of water around the outer edge 23 of the deck 22 cannot be prevented, these are kept from falling or 5 dripping from the deck by the provision of the trough 27 which receives the drops and from which they are conducted by the pipe 29 back to the source of supply. As the outer wall of the outer trough has its top edge in a plane below that along which the moisture laden air leaves the deck, the trough will not interfere with the efficient operation of the mechanism. 10

It will be apparent from the illustration of the invention that the accumulation of lint and dust 15 which occurs in the condensate receiving portions of every humidifier, will in the use of the present invention, be collected in the troughs 14 and 27 from which it can be removed without having to stop the operation of the humidifier 20 or shift any of the parts. Should it become necessary to reach the interior of the humidifier this is easily accomplished by sliding the bell 13 with the associate parts upwardly and maintaining the same in raised position by engaging the upper lugs 20 beneath the flange 16 of the trough 14 until the cleaning or other operation to be performed is completed. 25

What is claimed is:—

1. In a humidifier including a tubular moisture laden air conductor, a bell formed at the outlet end of said air conductor, a bottom having a raised cone-like central portion disposed in and concentric with said bell and merging into an outer portion constituting a deck, said bell having its lower edge in spaced relation with the bottom adjacent the inner edge of the deck whereby air passing between the bottom and the bell will flow across the top surface of the deck, and a trough disposed beneath the outer edge of the deck. 30

2. In a humidifier having a moist air conducting cylinder, a bell formed at the discharge end of said cylinder, a trough disposed about the lower edge of said bell and having the said edge 45 therein, there being an area between the bell and the trough to permit moisture to flow from the bell into the trough, a bottom having an up-pressed central portion extending into said bell and a surrounding deck portion, said bottom 50 deck portion being in spaced relation with said trough, and a drip receiving trough arranged concentrically with the bottom beneath the outer edge of the deck.

3. In a humidifier having a moist air conducting cylinder, a bell formed at the discharge end of said cylinder, a trough disposed about the lower edge of said bell and having the said edge 55 therein, there being an area between the bell and the trough to permit moisture to flow from the bell into the trough, a bottom having an up-pressed central portion extending into said bell and a surrounding deck portion, said bottom deck portion being in spaced relation with said trough, and a drip receiving trough 60 arranged concentrically with the bottom beneath the outer edge of the deck, said deck having its top surface disposed at an upward and outward inclination, and said last trough having an outer wall edge in a plane beneath the plane of the 65 top surface of the deck. 70

4. In a humidifier, a bottom imperforate throughout and comprising a central cone-like portion merging at its periphery into a flat outwardly extending and upwardly inclined deck 75

across which moisture laden air flows, and a drip gutter surrounding the periphery of the deck and disposed in a plane below the same and receiving all moisture condensed on the 5 cone and deck.

5. In a humidifier, a bottom imperforate throughout and comprising a central cone-like portion merging at its periphery into a flat outwardly extending and upwardly inclined deck 10 across which moisture laden air flows, and an annular drip gutter disposed beneath the periphery of the deck and having an inner wall joined at its top edge to the underside of the deck inwardly of the peripheral edge of the same.

15. 6. In a humidifier, a bottom comprising an imperforate body of sheet metal having an up-pressed cone-like central area merging into a flat outwardly extending and upwardly inclined deck, and a gutter surrounding the deck at its 20 periphery and disposed below the plane of the same and receiving all of the moisture condensed on the cone and deck from moisture laden air passing thereover.

7. A humidifier, comprising a vertically disposed tubular body through which moisture laden air passes, said body being flared to form a bell at its lower end, a gutter surrounding the lower edge of said bell and having an inner inwardly inclined wall disposed within the bell 25 and in spaced relation with the wall of the same, means coupling the bell with said gutter wall at spaced intervals to maintain the bell and gutter wall in spaced relation, an imperforate bottom comprising a central cone-like portion 30 disposed concentrically within the bell and an outwardly extending upwardly inclined deck portion, said deck and gutter being in spaced relation, and a gutter surrounding the outer edge of the deck and disposed in a plane beneath the same.

40. 8. A humidifier, comprising a vertically disposed tubular body through which moisture laden air passes, said body being flared to form a bell at its lower end, a gutter surrounding the

lower edge of said bell and having an inner inwardly inclined wall disposed within the bell and in spaced relation with the wall of the same, means coupling the bell with said gutter wall at spaced intervals to maintain the bell 5 and gutter wall in spaced relation, an imperforate bottom comprising a central cone-like portion disposed concentrically within the bell and an outwardly extending upwardly inclined deck portion, said deck and gutter being in 10 spaced relation, a gutter surrounding the outer edge of the deck and disposed in a plane beneath the same, and draining means extending from said first gutter downwardly to and contacting with the top of said deck whereby condensed 15 moisture in the first gutter will be transferred to the surface of the deck without interference from air passing over the deck.

9. A humidifier, comprising a vertically disposed tubular body through which moisture laden air passes, said body being flared to form a bell at its lower end, a gutter surrounding the lower edge of said bell and having an inner inwardly inclined wall disposed within the bell and in spaced relation with the wall of the same, means coupling the bell with said gutter 20 wall at spaced intervals to maintain the bell and gutter wall in spaced relation, an imperforate bottom comprising a central cone-like portion disposed concentrically within the bell 25 and an outwardly extending upwardly inclined deck portion, said deck and gutter being in spaced relation, a gutter surrounding the outer edge of the deck and disposed in a plane beneath the same, hanger members connected 30 with said bottom and extending upwardly therefrom, said tubular body being divided into two telescopically connected sections, and means for coupling the edge of the first gutter with the hanger elements for maintaining one of the said 35 sections of the tubular body in a desired relation with respect to the other.
